UNITED STATES PATENT OFFICE.

VICTOR M. TUTHILL, OF GRAND RAPIDS, MICHIGAN, ASSIGNOR TO BALDWIN, TUTHILL & BOLTON, OF GRAND RAPIDS, MICHIGAN, A CORPORATION OF MICHIGAN.

GRINDING-WHEEL-TRUING DEVICE.

Application filed April 12, 1919. Serial No. 289,723.

To all whom it may concern:

Be it known that I, VICTOR M. TUTHILL, a citizen of the United States of America, residing at Grand Rapids, in the county of Kent and State of Michigan, have invented certain new and useful Improvements in Grinding-Wheel-Truing Devices; and I do hereby declare the following to be a full, clear, and exact description of the invention, 10 such as will enable others skilled in the art to which it appertains to make and use the same.

This invention relates to a grinding wheel truing device for use in finishing grinding 15 wheels and giving the surfaces of the same any desired and varying degree of coarseness. It is an object and purpose of the invention to make a device of this character which may be used for finishing either the 20 face or periphery of a grinding wheel, and also one which may be used for finishing surfaces on a grinding wheel which may be located at an angle to each other, or concave surfaces, the construction of the device being 25 such that it may be held by the operator so as to reach practically any part of the wheel desired and this irrespective of the particular form of the edge of the grinding wheel, which may be of convex form, V- 30 shaped, or the like.

For an understanding of the invention, reference may be had to the following description taken in connection with the accompanying drawing, in which,

35 Fig. 1 is a plan of the device, and

Fig. 2 is a fragmentary horizontal section through the device illustrating the method of rotatably mounting the rotating truing wheel of the device.

40 Like reference characters refer to like parts in the different views of the drawing.

In the construction a spindle 1 is used between the ends of which a stop collar 2 is formed from which a cylindrical portion 3, 45 larger in diameter than the spindle 1 but smaller than the collar, projects, a cone 4 joining it with an extension 1^a of the spindle, the end of which is threaded as indicated at 6. This spindle passes through a sleeve 7 one end of which is formed with an enlarged head 8, while the other end is threaded for the reception of an interiorly threaded sleeve 9 which also has an enlarged head 10 similar to the head 8. The sleeve is

held on the first sleeve 7 by a set screw 11. 55 Between the heads 8 and 10 a wheel of emery or carborundum is located, sleeve 7 passing therethrough, and by moving the sleeve 9 along sleeve 7 so as to bring head 10 against one side of the wheel, the other side bearing against the head 8, a substantially rigid connection of the wheel to the sleeve 7 is made.

One end of sleeve 7 is bored to receive the cylindrical portion 3 and shaped to fit the cone 4. The other end is machined so that a member 13 having a cone 14 may be received therein, said member threading on to the threaded end 6 of the spindle. This makes a rotatable mount for the sleeve 7 70 and attached wheel 12, using cone bearings. A lock nut 15 is used to hold the cone nut 13 in place. In securing the wheel 12 between the heads 8 and 10 it is desirable to interpose paper washers 16, as shown and in 75 practice this is done.

The spindle 1 at the end opposite to the threaded end 6 is adapted to be connected to a handle member comprised of two arms 17 and 18 located at substantially right angles to each other. The axis of the spindle is in practical alinement with the center line of arm 17, and the end of the spindle is inserted into an opening bored or otherwise formed in the end of arm 17, being held in 85 place by a set screw 19. Each of the arms 17 and 18 terminate at their outer ends in balls 20 of convenient size for an operator of the tool to grasp in his hands.

With this device, the operator may bring 90 the wheel 12 into peripheral contact with the periphery of a larger grinding wheel, and if the axes of the two wheels are parallel so that both wheels turn with the same peripheral speed, the surface of the grinding wheel is given a comparatively coarse 95 grinding surface. If so located that the axis of the wheel 12 is at an angle to the axis of the grinding wheel, the wheel 12 turns at a less peripheral speed than the larger grinding wheel, the grinding surface made is finer, the degree of fineness being 100 dependent on the different angles of location of the two wheels. The formation of the handle member also permits the operator to use the wheel 12 against the sides of the grinding wheel; or in case the periphery of 105 the grinding wheel is V-shaped or is of con-

vex form, or of other forms than straight across, it is possible to use the device against any part of the wheel, due to the form of the handle member. Moreover, the operator who uses this device does not have to bring any part of his body in front of the grinding wheel, but may position himself wholly to one side, this being a feature of safety flowing from the construction and mounting of the wheel on the handle member. All of these features combine to make the device one of practical merit and value.

Of course, many variations in the angle that the arms 17 and 18 make with each other may be resorted to without changing the invention so long as the wheel is placed beyond the ends of the arms. The right angle location of the arms is preferred, however, as the positioning of the wheel against a grinding wheel is best controlled with such arrangement.

I claim:

1. In combination, a handle member comprising two arms located at substantially right angles to each other and having connection to each other, a spindle projecting

from the handle member in alinement with one of the arms, and a wheel rotatably mounted on the spindle close to the handle member.

30

2. In combination, a handle member comprising two arms connected together adjacent one end of each arm, and located at an angle to each other, a spindle attached to the handle member and extending therefrom, and a wheel rotatably mounted on the spindle close to the handle member, said handle member having both arms thereof located to one side of the wheel.

35

3. In combination, a handle member comprised of two arms connected together and located at an angle to each other, a spindle detachably connected to and projecting from the handle member, a wheel rotatably mounted on the spindle close to the handle member, with the arms of said handle member located at one side of the wheel, and means for fixing the spindle on the handle member, substantially as described.

40

In testimony whereof I affix my signature.

VICTOR M. TUTHILL.
